THOMAS SCOTT GRIEVE, OF LEICESTER, ENGLAND, ASSIGNOR TO T. GRIEVE & CO.
LIMITED, OF LEICESTER, ENGLAND

YARN-FEEDING MEANS FOR CIRCULAR-KNITTING MACHINES

Application filed March 15, 1929, Serial No. 347,398, and in Great Britain March 31, 1928.

This invention relates to yarn feeding means for circular knitting machines and has for its object the provision of an improved feeder, more particularly, though not necessarily exclusively, for use in plating and reverse plating, and also improved means for controlling the yarns in reverse plating.

The invention is principally intended for application to circular machines of the double cylinder type, but it is not limited in this respect as it may be applied to other circular machines.

In a circular machine employing a feed plate furnished with an opening extending substantially circumferentially for the purpose of allowing the yarn, or one of the yarns, which passes through it to change its position, such as during reciprocating action or in reverse plating, the opening requires to be of such length that it cuts across the downward path of the needles, the latches of which are close to the inside of the feed plate, and there is thus a possibility of collision between the latches and the lower edge of the opening.

The present invention includes as a feature a feeder wherein the opening for the yarn or yarns is so formed that collision of the needle latches therewith is prevented.

According to this invention there is provided a feeder having a yarn feeding opening the lower portion at least of which is formed in a part of the feeder set back from the inner face so as to be well away from the vertical plane in which the needle latches descend. The feeder may consist of a single feed plate with the said opening formed in an integral part set back as aforesaid, but said feeder preferably consists of separate parts respectively formed with apertures and adapted for use in juxtaposition with the inner face of one part set back from, i. e. located further away from the needles than, the inner face of the other part, so that the two apertures together form a yarn feeding opening the lower portion of which is out of the plane of the latches of the descending needles.

For producing reverse plating, it is preferred to use the improved feeder in conjunc-

tion with movable yarn fingers, that is, a yarn finger to control each yarn. In such arrangement, for supplying two yarns for example, the movable fingers are controlled so that they are alternately advanced and retracted towards and from the opening, i. e. one is advanced when the other is retracted. The feed location of the yarn from the advanced finger is determined by said finger, while the feed location of the yarn from the retracted finger is determined by one end of the opening. On the fingers changing their positions the feed locations of the yarns are changed, thereby producing reverse plating.

The invention also includes as a feature the provision for reverse plating of pivoted fingers operated for changing the positions of the yarns by a common member, for example a lever, preferably actuated by a cam and controlled by pattern mechanism as will be hereinafter explained. Said fingers are preferably mounted on the top cam box of the machine and used in association with the feeder forming part of this invention.

In further describing the invention reference will be hereinafter made to the accompanying drawings wherein,

Figure 1 is a sectional elevation of a concrete example of the feeder comprising two parts.

Figure 2 is a front elevation of the two parts separated.

Figure 3 is a front elevation of the two parts in co-relation in a circular knitting machine.

Figures 4 and 5 are respectively side and front elevations of a reverse plating arrangement employing the improved feeder and pivoted yarn fingers in combination in a circular knitting machine of the superposed cylinder type.

Referring to Figures 1, 2 and 3, the feeder illustrated comprises two parts 1 and 2. The part 1 is formed with a notch 3 in the lower edge thereof, and the part 2 has at the upper edge a notch 4. When the two parts are correlated or combined in the machine, as represented in Figures 1 and 3, the inner face 5 of the part 2 is located further away from the needles (one of which is shown at 6 in Fig-

ure 1) than the inner face 7 of the part 1, and there is formed an opening or mouthpiece 8 (Figure 3) the lower portion of which, i. e. that constituted by a notch 4 in the part 2, is out of the plane of the latches of the descending needles, so that the risk of collision of the needle latches with this portion of the feeder is eliminated. As illustrated in Figure 3, the two parts 1 and 2 are fixed in the machine so that the said notches are substantially in register with each other. That is to say, the part 2 is fitted in front of and slightly over the part 1 so that the upper edge of the former overlaps the lower edge of the latter. In this way the lower portions 9 and 10 of the part 1 serve as latch guards over the extremities of a notch 4. If desired or necessary the parts may be fixed so that the notch 4 is immediately below the notch 3 instead of the two notches being substantially in register as aforesaid. As will be observed the notch 4 is longer, considered circumferentially, than the notch 3, the purpose of this being, of course, to enable the yarn which is supplied to the needles in reciprocating knitting, to traverse the notch 4 from one end to the other. Conveniently in a circular knitting machine of the superposed cylinder type, the two parts of the feeder are respectively fixed to a plate 11 or like carrier, the part 1 being attached on the inside of the plate by screws 12, and the part 2 on the outside of the plate by screws 13. The plate 11 is in turn attached to the top cam box 14 of the machine by screws 15.

35 Preferably, for reverse plating the feeder is constructed in the manner already described with reference to Figures 1 to 3, that is, one portion of the opening is formed in a part 1 and the other in a part 2, the upper portion 3 being comparatively short, and the lower portion 4 being longer to enable the yarn which passes therethrough to change its position as aforesaid during reciprocating action of the machine.

40 This feeder is used in combination with 45 yarn fingers of pivoted form each constructed and mounted to turn on a horizontal axis on the top cam box, so that the delivery end moves towards and from the feeder and enters the opening or mouthpiece 8, the path of movement being a substantially horizontal arc. The fingers are operated by suitable means in a controlled manner by a cam or equivalent and intermediate connections.

50 In the combination illustrated in Figures 4 and 5, which also illustrate yarn fingers arranged and operated in a manner forming part of the invention, there are two yarn fingers 16 and 17, respectively fulcrumed at 18 and 19 in a bracket 20 attached to the top cam box 14. The finger 16 has a pin 21 therein which enters a slot 22 in the finger 17, said pin and slot being above the fulcrum 18. Another pin 23 is also fixed in the finger 16, so as to be located below the fulcrum 18, and this

pin enters a slot 24 in one arm of an actuating bell crank lever 25 fulcrumed at 26 in a bracket 27 attached to the cam box 14. At the lower extremities the fingers are furnished with hollow or tubular yarn guides 28 and 29, arranged so as to converge towards the opening or mouthpiece 8 constituted by the notches 3 and 4 (Figure 2) in the feeder parts 1 and 2 as hereinbefore set forth. Yarns *a* and *b* are represented as passing through the respective guides. The arrangement is such that as the bell crank lever 25 is rocked the two fingers 16, 17 are moved in opposite directions simultaneously. When however, the bell crank lever is held stationary at either extremity of its movement, one of these fingers is held in an advanced position so that its guide enters the opening 8 while the other is retracted so that its guide is withdrawn from the said opening. The yarn controlled by the advanced finger passes through the opening 8 and behind the portion 10 of the part 1 to the needles, while the yarn from the retracted finger passes, in circular knitting, through the right hand extremity of the notch 4 in the part 2, and between the latter and the said portion 10 to the needles. During reciprocating knitting the said yarn passes from each extremity of the notch 4 in turn i. e. between the part 2 and the portions 9 and 10 respectively of the part 1. These portions may be bevelled to provide clearance for the yarn. In Figures 4 and 5, the yarn *a* is represented as passing through the right hand extremity of the notch 4, and the yarn *b* as passing through the opening 8. The part 2 of the feeder has a groove or channel 30 leading to the notch 4 to accommodate the yarn guides 28 and 29.

55 The actuating lever e. g. the lever 25, may be actuated for the purpose above mentioned in any suitable manner in timed relation with the revolutions of the machine to change the feeding positions of the yarns at the times required, through the medium of a link 31.

60 What I claim then is:

1. In a circular knitting machine, co-axial needle cylinders and cam boxes, a series of needles and means for feeding yarns in plating relation, comprising a pair of fingers pivoted on the rib cam box, the pivot for each finger being disposed so that upon operation of the fingers to change the positions of the yarns the ends which deliver the yarns move substantially radially towards and away from the needles, the path of movement being a substantially horizontal arc.

65 2. In a circular knitting machine, co-axial needle cylinders and cam boxes, a series of needles, and means for feeding yarns in plating relation, comprising two pivoted fingers extending from separate axes on the rib cam box, said axes being disposed so that upon operation of the fingers to change the positions of the yarns the ends which deliver the

yarns move substantially radially towards and away from the needles, the path of movement being a substantially horizontal arc.

3. In a circular knitting machine, superposed co-axial needle cylinders and cam boxes, a series of needles, and means for feeding yarns in plating relation, comprising two pivoted fingers depending from separate horizontal axes on the top cam box so that upon operation of the fingers to change the positions of the yarns the ends which deliver the yarns move substantially radially towards and away from the needles, the path of movement being a substantially horizontal arc.

4. In a circular knitting machine in combination, superposed co-axial needle cylinders and cam boxes, a series of needles, means for feeding yarns in plating relation comprising two pivoted fingers depending from separate horizontal axes on the top cam box, the axes being disposed one above the other so that upon operation of said fingers to change the positions of the yarns, the ends which deliver the yarns move respectively in opposite directions in a path which is substantially radial with respect to the needles and also a substantially horizontal arc, and a lever common to both of said fingers for actuating the same.

5. In a circular knitting machine in combination, superposed co-axial needle cylinders and cam boxes, a series of needles, means for feeding yarns in plating relation comprising two pivoted fingers depending from separate horizontal axes disposed one above another on the top cam box, so that the lower ends of the fingers can move substantially radially towards and from the needles, the path of movement being a substantially horizontal arc, said fingers being also connected between the axes by a pin and slot connection, and a pivoted lever engaging one of said fingers below the aforesaid axes for actuating the fingers to change the positions of the yarns.

6. In a circular knitting machine in combination, axially opposed needle cylinders and cam boxes, a series of latch needles, means for feeding yarns in plating relation comprising a pair of fingers pivoted on the rib cam box, the pivots for the fingers being disposed so that upon operation of the fingers to change the positions of the yarns the ends which deliver the yarns move substantially radially with respect to the needles, the path of movement being a substantially horizontal arc, and a yarn feeder comprising separate parts respectively formed with notches and juxtaposed with the inner face of one set back from the inner face of the other so that the two notches together form an aperture the lower portion of which is out of the plane in which the needle latches travel, for the purpose set forth.

7. In a circular knitting machine, co-axial needle cylinders and cam boxes, a series of needles, means for feeding yarns in plating relation, comprising two pivoted fingers extending from separate axes on the rib cam box, said axes being disposed so that upon operation of the fingers to change the positions of the yarns the ends which deliver the yarns move substantially radially with respect to the needles, the path of movement being a substantially horizontal arc, and a yarn feeder comprising separate parts respectively formed with notches and juxtaposed with the inner face of one set back from the inner face of the other so that the two notches together form an aperture the lower portion of which is out of the plane in which the needle latches travel, for the purpose set forth.

8. In a circular knitting machine, superposed co-axial needle cylinders and cam boxes, a series of needles, means for feeding yarns in plating relation, comprising two pivoted fingers depending from separate horizontal axes on the cam box so that upon operation of the fingers to change the positions of the yarns the ends which deliver the yarns move substantially radially with respect to the needles, the path of movement being a substantially horizontal arc, and a yarn feeder comprising separate parts respectively formed with notches and juxtaposed with the inner face of one set back from the inner face of the other so that the two notches together form an aperture the lower portion of which is out of the plane in which the needle latches travel, for the purpose set forth.

9. In a circular knitting machine in combination, superposed co-axial needle cylinders and cam boxes, a series of needles, means for feeding yarns in plating relation comprising two pivoted fingers depending from separate horizontal axes disposed one above another on the top cam box, so that upon operation of said fingers to change the positions of the yarns, the ends which deliver the yarns move respectively in opposite directions substantially radially with respect to the needles, the path of movement being a substantially horizontal arc, a lever common to both of said fingers for actuating the same, and a yarn feeder comprising separate parts respectively formed with notches and juxtaposed with the inner face of one set back from the inner face of the other so that the two notches together form an aperture the lower portion of which is out of the plane in which the needle latches travel as the needles descend, for the purpose set forth.

10. In a circular knitting machine in combination, superposed co-axial needle cylinders and cam boxes, a series of needles, means for feeding yarns in plating relation comprising two pivoted fingers depending from separate

horizontal axes disposed one above another on the top cam box so that the lower ends of the fingers can move substantially radially towards and from the needles, the path of movement being a substantially horizontal arc, said fingers being also connected between the axes by a pin and slot connection, a pivoted lever engaging one of said fingers below the aforesaid axes for actuating the fingers to change the positions of the yarns, and a yarn feeder comprising separate parts respectively formed with notches and juxtaposed with the inner face of one set back from the inner face of the other so that the two notches together form an aperture the lower portion of which is out of the plane in which the needle latches travel as the needles descend, for the purpose set forth.

In testimony whereof I affix my signature.

THOMAS SCOTT GRIEVE.
